UNITED STATES PATENT OFFICE.

PAUL WINAND, OF COLOGNE, GERMANY.

METHOD OF CONTROLLING COMBUSTION-ENGINES.

970,154.

Specification of Letters Patent. Patented Sept. 13, 1910.

No Drawing.

Application filed March 8, 1907. Serial No. 361,223.

To all whom it may concern:

Be it known that I, PAUL WINAND, engineer, a subject of the King of Belgium, residing at 1 Sudermannstrasse, Cologne-on-the-Rhine, Germany, have invented certain new and useful Improvements in Methods of Controlling Combustion-Engines; and I do hereby declare the following to be a full, clear, and exact description of the invention, such as will enable others skilled in the art to which it appertains to make and use the same.

Combustion engines which are driven by atmospheric air as the oxygen vehicle are, as is well known, so operated that there is always a certain excess of air present in the charge, in order that the fuel may be completely utilized, that is, in order that each individual particle of fuel may be united with the amount of oxygen necessary to burn it. The employment of the excess above the theoretically necessary quantity of air is justified because, in practice, it is not possible, in consequence of lack of exactness in the regulating devices on the one hand, and in consequence of occasional inequalities in the mixture of the charge, or in the composition of one of the elements of the charge, on the other hand, to introduce fuel and air into the combustion chamber in such proportions that a complete union of the two elements takes place, that is, that the products of combustion contain neither unconsumed fuel nor unutilized oxygen. In order, therefore, to be sure that no unconsumed fuel is contained in the products of combustion, one is led to give to the charge an excess of oxygen so that the products of combustion, if they must contain an unutilized element of the charge, shall only contain unutilized air.

In operating combustion engines in which combustible fuel is burned by means of an oxygen vehicle carried along with the engine, as in submarine boats, it is important to utilize the oxygen completely in order to obtain the smallest possible weight of stored material. A complete utilization of the combustible is of minor importance because 3½ kilograms of oxygen are required for the complete combustion of one kilogram of liquid hydrocarbon.

The object of the present method is to avoid wasting the oxygen, notwithstanding any inaccuracy in the working of the governing device and notwithstanding any lack of uniformity in the mixture of the oxygen

or oxygen vehicle with the combustible, and also notwithstanding any possible lack of uniformity in the nature of the combustible and of the oxygen vehicle.

60

The invention consists primarily in controlling the supply of the oxygen vehicle to the explosive charge in such manner that the amount supplied is not quite sufficient to completely burn the combustible fed to the engine. When thus using an excess of combustible the amount of developed heat, and consequently the amount of power developed, is determined primarily by the amount of oxygen fed to the engine. The engine may be controlled, therefore, by regulating the amount of the oxygen vehicle supplied, and the amount of the combustible may then be regulated in such manner that the excess of combustible remains within desired limits, so that an approximately complete utilization of the oxygen vehicle is obtained. It is, however, practically necessary, as pointed out in my co-pending application, Serial Number 272,621, filed August 3d, 1905, when using an oxygen vehicle of high oxidizing capacity, to employ also a diluting medium to reduce the temperature which would otherwise exist. The diluting medium may, as pointed out in the aforesaid application, consist of an excess of the combustible, thereby avoiding the necessity for a separate receptacle for the diluting medium with a resultant economy in weight. The diluting medium may, however, more advantageously consist of a third substance (such as sea water or the cooled products of combustion) since such a diluting agent is cheaper and is usually present in the place or locality of use without necessitating a separate receptacle. But whether the combustible itself

70

is used as the diluting medium, or a separate substance is employed, the characteristic feature of my invention broadly considered is that the charge always contains more combustible than is necessary to unite with all of the oxygen present, thereby assuring a complete utilization of the oxygen. More specifically, and in its preferred embodiment, it consists in the utilization not only of the excess of combustible above that necessary to unite with all of the oxygen present, but also, in conjunction therewith the employment of a third constituent of the charge having as its function not only a diluting effect but also the reduction of the

What I claim is:

1. The method of actuating combustion engines for submarine boats and the like, in which the oxidizing element of the combustion charge is an oxygen vehicle having a greater oxidizing capacity than air, which consists in introducing into the working cylinder of the engine a given quantity of the combustible element and likewise introducing into said working cylinder a quantity of the oxygen vehicle in amount less than that necessary to unite with all of the combustible element present, and thereupon effecting the combustion of the charge in said working cylinder, whereby, for said combustion charge of the working cylinder the oxygen of the oxygen vehicle is completely utilized and a surplus of unconsumed combustible remains as a diluent.
2. The method of actuating combustion engines for submarine boats and the like, in which the oxidizing element of the combustion charge is an oxygen vehicle having

a greater oxidizing capacity than air, which consists in introducing into the working cylinder of the engine a given quantity of the combustible element and likewise introducing into said working cylinder a quantity of the oxygen vehicle in amount less than that necessary to unite with all of the combustible element present, and thereupon effecting the combustion of the charge in said working cylinder, whereby, for said combustion charge of the working cylinder the oxygen of the oxygen vehicle is completely utilized and a surplus of unconsumed combustible remains as a diluent, and further diluting the charge with a separate third constituent.

In testimony whereof I have affixed my signature, in presence of two witnesses.

PAUL WINAND.

Witnesses:

BESSIE F. DUNLAP,
LOUIS VANDORY.
